DECORATIVE PANEL FOR A TOASTER OR THE LIKE

Andrew S. Knapp, 3501 Bent Ave., St. Louis, Mo.

Filed June 15, 1960, Ser. No. 60,978

Term of patent 14 years

(Cl. D81—10)

FIGURE 1 is a perspective view showing a decorative panel for a toaster or the like.

FIGURE 2 is a top edge view of the decorative panel disclosed in FIGURE 1;

FIGURE 3 is a front elevation view of the same; and

FIGURE 4 is a side edge view of the same.

The toaster end panel shown in broken lines in FIGURE 1 is for illustrative purposes only.

I claim:

The ornamental design for a decorative panel for a toaster or the like, substantially as shown and described.
